UNITED STATES PATENT OFFICE.

WALTER T. GODDARD, OF VICTOR, NEW YORK.

CABLE-CLAMPING DEVICE.

1,305,713.

Specification of Letters Patent. Patented June 3, 1919.

Application filed December 8, 1917. Serial No. 206,206.

To all whom it may concern:

Be it known that I, WALTER T. GODDARD, of Victor, in the county of Ontario and State of New York, have invented certain new and useful Improvements in Cable-Clamping Devices; and I do hereby declare the following to be a full, clear, and exact description of the same, reference being had to the accompanying drawings, forming a part of this specification, and to the reference-numerals marked thereon.

The object of my invention is to provide an improved form of cable clamp for use especially in connection with the suspension of electric conductors from insulator supports. More particularly the invention has for its purpose to provide a structure which can be economically manufactured and possessing the necessary strength and stiffness to withstand the usual strains to which it may be subjected. Still a further object of my improvement lies in adopting an arrangement which permits the device to be manufactured from sheet metal through a series of stamping operations. To these and other ends the invention consists in certain improvements and combinations of parts, all as will be hereinafter more fully described, the novel features being pointed out in the claims at the end of the specification.

In the drawings:

Figure 1 is a side elevation showing my invention applied in operative relationship;

Fig. 2 is an enlarged side elevation of the clamping device;

Fig. 3 is a bottom plan view;

Fig. 4 is a vertical sectional view on line 4^a-4^a of Fig. 2;

Fig. 5 is an end elevation, and

Fig. 6 is a plan view of the blank from which the clamp is formed.

Similar reference numerals in the several figures indicate the same parts.

For a general understanding of the application of the invention, it is sufficient to state that 1 designates an insulator support which is suitably attached to some stationary element and suspended from the support is the clamping device to which is secured a conducting cable 2.

I preferably employ a blank plate such as shown in Fig. 6, which is subjected to a series of stamping operations to obtain the form of device which is indicated in the remaining figures. Referring to Fig. 6, the portion 3 is bent outwardly along the dotted

line 4, forming a curved flange 5 at the apex of the triangular opening of the plate or body portion, Fig. 2, which affords a bearing for the suspension member or supporting clevis 6. The portion 7 of the blank is bent outwardly to one side along the dotted line 8, affording a substantially flat flange 9 which is provided with bolt openings 10 for a purpose that will appear presently. 60 The lower portion 11 of the blank is bent upwardly and outwardly along the dotted line 8, affording a second flange at the base of the opening 12, extending in a direction opposite to that of the flat flange 9, and is 70 recessed or substantially V-shaped, affording a seat 13 for the conductor 2. The body portion of the plate and also the opening 12 therein are preferably of substantially triangular shape, and the ends of the seat 13 75 are flared downwardly at the portions 14, so that if the conductor is broken on one side of the clamp, the remaining end will be held by the clamp, which will swing partially about the clevis 6, and the surface 14 will 80 afford a bearing for that portion of the cable which remains held by the clamp. The portions 15 of the blank are bent laterally along the dotted line 16 to afford stiffening flanges. 85

The conductor is held in position in its recess by a clamping member or plate which is bent upon itself, or U-shaped, to provide an upper cable engaging portion 17. The portion 17 overlies the flange 9 and has a 90 curved extremity 18 which engages the upper side of the conductor. The clamping member also preferably includes an integral lower portion 19 which may extend underneath the flange 9 and abuts against the 95 same when the parts are in clamping relationship. The clamping member is held rigidly against the conductor and against the flange 9 by means of bolts passing through openings in the flange 9 and in the clamping 100 member and held in place by the nuts 20. The bolt heads 21 are preferably curved on their inner faces and engage correspondingly curved surfaces on the clamping member 17 in order to effect a tight engagement 105 between the conductor and the clamping member, which latter is slightly resilient. When the nuts 20 are tightened, the lower portion 19 is held against the flat flange 9, preventing the clamping member from tilting, and retaining the conductor rigidly in the seat of the clamp. 110

The structure is an exceedingly practical and efficient one, and economical to manufacture, since it can be formed entirely from sheet metal in a manner that imparts to it 5 the required stability and strain resisting qualities.

I claim as my invention:

1. A cable clamping device comprising a sheet metal body having an opening therein, 10 an integral flange formed from the upper edge of the opening to provide a bearing for a suspension member, a clamp supporting integral flange formed from the lower edge of the opening, a cable supporting integral flange formed with a seat to receive the cable, a clamping member for retaining the cable in its seat, and securing devices 15 co-operating with the clamp supporting flange and the clamping member for holding the latter in clamping engagement with the cable.
2. A cable clamping device comprising a plate or body portion, formed of sheet metal and having a substantially triangular central opening, an integral curved flange at the apex of said opening affording a bearing for a support, an integral substantially V-shaped flange extending from one side of the base of the opening forming a seat for 20 a cable, an integral flange extending from the opposite side of the base of the opening, a removable clamping member consisting of a substantially U-shaped plate affording an upper portion which engages a cable in said 25 seat and a lower portion which engages the under face of said flat flange, and securing devices which hold the clamping member in engagement with the flange and the cable.
3. A cable clamping device comprising a 30 body portion substantially in the form of a triangular plate, a bearing surface adjacent the top of the plate for engagement with a suspension member, a clamp supporting flange adjacent the bottom of the plate extending transversely of the latter, a cable 45 supporting flange also adjacent the bottom of the plate extending transversely of the latter and provided with a seat for the cable, a clamping member extending transversely of the plate and securing devices co-operating with the clamp supporting flange and the clamping member to hold the latter in clamping engagement with the cable in its seat.
4. A cable clamping device comprising a 50 substantially plane body portion having an opening therein, a bearing surface adjacent the top of the plate for engagement with a suspension member, a clamp supporting flange on one side of the plate, a cable supporting flange on the side of the plate opposite the clamp supporting flange and provided with a seat for the cable and a clamping member carried by the clamp supporting flange and extending through the opening in the plate to engage and hold the cable 55 in its seat.
5. A cable clamping device comprising a body portion having an opening therein, a bearing portion adjacent the top of the body 60 for co-operation with a suspension member, a cable supporting flange integral with the body and provided with a seat for the cable, an integral clamp supporting flange, a clamping member extending through the 65 opening in the body, and securing devices co-operating with the clamp supporting flange and with the clamping member to hold the latter in clamping engagement with the cable.

WALTER T. GODDARD.
